UNITED STATES PATENT OFFICE.

WILLIAM BERNSTEIN, OF NEW YORK, N. Y.

HEAD-COVERING.

No. 908,197.

Specification of Letters Patent.

Patented Dec. 29, 1908.

Application filed March 25, 1908. Serial No. 423,246.

To all whom it may concern:

Be it known that I, WILLIAM BERNSTEIN, a citizen of the United States, and a resident of the city of New York, borough of Manhattan, in the county and State of New York, have invented a new and Improved Head-Covering, of which the following is a full, clear, and exact description.

The invention relates to wearing apparel and its object is to provide a new and improved head covering for infants and children, arranged to properly fit the head and to allow convenient washing and cleaning of the head covering with a view to insure long service and to maintain the head covering in a neat, tidy condition.

The invention consists of novel features and parts and combinations of the same, which will be more fully described herein-after and then pointed out in the claims.

A practical embodiment of the invention is represented in the accompanying drawings forming a part of this specification, in which similar characters of reference indicate corresponding parts in all the views.

Figure 1 is a perspective view of the improvement; Fig. 2 is a sectional plan view of the same on the line 2-2 of Fig. 1; and Fig. 3 is a plan view of the body of the head covering in an extended position.

The body A of the head covering is preferably formed of a single piece of fabric material capable of being washed, and the said body is preferably provided with an interior lining B, as indicated in Figs. 1 and 2. The piece of fabric material for forming the body A is cut, as indicated in Fig. 3, to form a top C, sides D, D', a divided back consisting of the members E, E', and a back covering flap F which extends from the rear of the top C, while the members E, E' of the divided back extend from the rear of the sides D and D', respectively. When the piece of fabric material forming the body A is folded along the dotted lines indicated in Fig. 3, then the back members E and E' meet along their edges E², E³, and as the said edges E², E³ are at obtuse angles relative to the bottom edges E⁴, E⁵ of the said back members, it is evident that the lower rear portion of the body A is drawn inward, to properly fit the rear of the head of the wearer, as will be readily understood by reference to Fig. 1. The meeting edges

E², E³ are provided with tying bands G, G', 55 to fasten the back members E and E' together, as indicated in Fig. 2, and the lower corners of the back covering flap F is provided with tying strings H, H' adapted to be tied with corresponding tying strings I, 60 I', arranged on the bottom edges E⁴ and E⁵ of the back members E and E'. To the front lower corners of the sides D and D' are removably attached tying ribbons J, J' by the use of suitable fastening devices K, 65 K', such as safety pins and the like. When the head covering is placed in position on the child's or infant's head, then the tying ribbons J, J' are tied under the chin in the usual manner.

In case the head covering becomes soiled, the tying ribbons J and J' are disconnected from the sides D, D' of the body A, and then the several sets of tying strings G, G', H, H' and I, I' are untied, to allow of unfolding 75 the several parts of the body A and to permit convenient washing thereof. When the body has been washed the parts can be tied together again, as above described, and then the tying ribbons J, J' are re-attached, to 80 complete the head covering.

Having thus described my invention, I claim as new and desire to secure by Letters Patent:

1. A head covering formed of a single 85 piece of fabric material having its central portion at the rear extended and provided in its rear edge at each side of and adjacent to the extension with notches, whereby a central overlying flap and back members, one 90 at each side of the flap, will be formed at the rear edge of the material, tapes secured to the rear edges of the members for securing them together with their edges in substantial engagement when folded inwardly, 95 and tapes secured to the corners of the flap and to the outer or lower edges of the back members for securing the flap in position over the back members.

2. A head covering having a body formed 100 of a single piece of a fabric material arranged to provide a top, sides, a back formed of two members extending integrally from the said sides and having their edges meeting when folded inwardly, a back covering 105 flap extending integrally from the said top for overlying the said divided back, the meeting edges of the said back members ex-

tending at obtuse angles relative to the bottom edges of the said back members, tying strings along the bottom edges of the back flap and the back members, and tying strings along the meeting edges of the back members.

In testimony whereof I have signed my

name to this specification in the presence of two subscribing witnesses.

WILLIAM BERNSTEIN.
